[57] CLAIM

The ornamental design for child's amusement spinning disc or the like, as shown and described.

DESCRIPTION

FIG. 1 is a perspective view of a child's amusement spinning disc or the like showing my new design;

FIG. 2 is a bottom plan view thereof;

FIG. 3 is a side elevational view thereof, inverted, the view in side elevation being the same around its entire perimeter; and

FIG. 4 is a view in top plan thereof.

FIG. 1.

FIG. 2.

FIG. 3.

FIG. 4.
